UNITED STATES PATENT OFFICE.

ALBERT J. MEIER, OF GLENDALE, MISSOURI.

ANNEALING-OVEN.

1,024,217.

Specification of Letters Patent. Patented Apr. 23, 1912.

Application filed June 5, 1911. Serial No. 631,284.

To all whom it may concern:

Be it known that I, ALBERT J. MEIER, a citizen of the United States, residing at Glendale, in the county of St. Louis and State of Missouri, have invented certain new and useful Improvements in Annealing Ovens, of which the following is a specification.

This invention relates to certain new and useful improvements in annealing ovens.

The object of the invention is to provide an improved structure in which the articles to be annealed are placed on a rotating carrier and moved through an annealing chamber, and to further provide an oven of this type in which the parts are constructed of tile and in which the latter is also utilized as a means for protecting the metal parts against the action of the heat.

20 In the drawings: Figure 1 is a front elevation of an oven constructed in accordance with the present invention, Fig. 2 is a side elevation, Fig. 3 is a central vertical sectional view, Fig. 4 is a horizontal sectional view taken on the line 4—4 of Fig. 3, Fig. 5 is a horizontal sectional view taken on the line 5—5 of Fig. 3, Fig. 6 is a vertical sectional view taken on the line 6—6 of Fig. 5, and Fig. 7 is a vertical sectional view 30 taken on the line 7—7 of Fig. 5.

The annealing oven is constructed of brick or other suitable material and is formed to have a central opening 1", and a circular heating chamber 1, which latter has a closed bottom formed by the two concentric spaced annuli 1'. The roof and side walls of the chamber 1 are constructed of tiles, the roof being of gable shape and being formed of a series of pairs of sloping tiles 2 having 35 their inner ends meeting at a point and secured together by a tongue and groove joint 3 and having their outer ends resting on the fire bricks 4 which form the side walls of the heating chamber.

40 In Fig. 5 the fire chamber is shown as provided with a partition 6, which divides the same into two compartments 7 and 8', each having a gas burner 9 extending thereto, though obviously any other suitable source 45 of heat may be utilized in place of the gas burners.

The annealing chamber, which is of circular form, has an open bottom which is pro-

vided by the space between the concentric annuli 1'. The roof of the annealing chamber is of gable-shape and is formed of a series of pairs of sloping tiles 8 having their inner ends meeting at a point and secured together by a tongue and groove joint 9', the outer ends of the tiles 8 being grooved 60 and resting on the tiles 10, which latter form the side walls of the annealing chamber. The lower ends of the tiles 10 and the annuli 1' which form the bottom of the heating chamber are provided with a tongue and groove joint as illustrated at 11 in the drawings. A series of spaced tiles or fire-bricks 6' are secured to the side walls of the heating chamber and abut the upper ends of tiles 10 and 8 of the annealing chamber in order 70 to hold the upper ends of the tiles 10 in proper position.

From Fig. 3 of the drawings it will be seen that the heating chamber is spaced from the sides and top of the annealing 75 chamber whereby heat passages are formed to permit the heat to circulate about the annealing chamber.

In Fig. 5 of the drawings the arrows illustrate the course of the heat, the latter passing from the burners 9 in opposite directions through the heating chamber and finally escapes up through the stack 12. Obviously, the partition 6, which may either be tile or fire-brick, causes the heat from one 80 compartment of the fire chamber to pass through one part of the heating chamber, and the heat from the other compartment of the fire chamber to pass through the other 85 part of the heating chamber, for which purpose the partition 6 abuts the tiles 10 which form the outer wall of the annealing chamber.

A partition 6" illustrated in Fig. 4 extends over the tiles 8, 8' at a point in alignment with the partition 6 and serves to direct the heat coming from the compartments 7 and 8', so that the heat will follow the course indicated by the arrows in Fig. 4.

As shown in Figs. 6 and 7, the lower 100 end of the stack 12 enters the roof of the heating chamber 1, the opening through which the stack projects being lined with fire-bricks 13, as seen in Fig. 6.

The present invention is especially adapted for annealing steel packages, though ob-

viously other articles may be annealed as well. The articles designated A to be annealed are placed on the tiles 14, which form or constitute the floor or platform of the 5 rotating carrier, the latter including an annular casting 15, preferably made in sections and formed with radial arms 16, which arms at their inner ends fit in notches provided therefor in a second casting 17 which 10 is rigidly mounted on the vertical shaft 18, the latter being arranged in the space 1" of the oven. A third casting 19 is mounted on the shaft 18, and has perforated portions 20, through which the upper ends of long 15 bolts 21 extend, the latter at their lower ends being passed through the perforations of enlarged portions 22 formed on the radial arms 16, the ends of the bolts 21 being rigidly secured to the parts 20 and 22, 20 whereby the casting 15 is supported and braced at its peripheral portion in an obvious manner.

The vertical shaft 18 rests in a toe bearing 23 formed in the concrete or other base 24, 25 the entire oven structure resting on the latter. At its upper end the shaft 18 bears a miter-gear 25, which meshes with a miter-gear 26 carried by a horizontal shaft 27, the shaft 27 being driven by a gear 28 af- 30 fixed thereto and a worm 29, which latter may be driven by any suitable means.

The upper end of the vertical shaft 18 is journaled in a bearing 30 that is supported by the I-beams 31, which latter are in turn 35 supported by the I-beams 32, which rest on the top of the oven and are disposed transverse to the I-beams 31, the horizontal shaft 27 being journaled in bearings 33, that are secured to the I-beams 31.

40 A conical shield 34 surrounds shaft 18 and rests on the casting 35, which latter surrounds the shaft 18 and is suspended by means of long vertical bolts 36, which latter have their upper ends supported from 45 the I-beams 31 and have their lower ends passed through the upper part of casting 35 and being secured to the latter. The shield 34 acts to prevent anything from dropping into or entering the base portion of the oven.

50 Casting 35 is formed with a horizontal annular shelf-like part 37 and with vertical annular faces 38 and 39, the latter having a horizontal annular ledge 40 on which tiles 41 seat, the latter at their upper ends 55 engaging the inner of the two annuli 1', which constitute the bottom of the heating chamber 1. The shelf-like part 37 has an annular tongue 42 which is received in an annular groove provided therefor in the 60 under face of said inner of the two annuli 1', which constitute the bottom of the heating chamber, whereby it will be seen that the inner annuli is supported in position against downward movement.

65 The tiles 14, which form the floor of the

rotating carrier, are preferably formed with openings 55 to permit of the passage of heat therethrough, and same are provided with grooves which receive a raised annular tongue 43 formed on an annular casting 44, 70 having an annular apron 45 formed with an annular horizontal ledge 46, on which the tiles 47 seat, the latter having their upper ends beveled and engaged with a 75 downwardly inclined projection 48 formed on the bottom faces of the tiles 14, whereby the tiles are held against outward movement. The annular ledge 46 is provided with a raised annular lip 51, which engages 80 the outer sides of the lower ends of the tiles 47, to hold same against outward movement. The annular ledge 40 of casting 35 is provided with an annular lip 49 to engage the outer sides of the lower ends of tiles 41 85 to hold the latter against outward movement, and the upper ends of tiles 41 are beveled to engage with the downwardly inclined projection 50 of the inner annuli 1' of the bottom of the heating chamber. 90

It will be observed from the foregoing that the tiles 41 and 47 act to protect their respective castings 35 and 15 against the action of the heat, and, moreover, said tiles are held in position by virtue of the interlocking connections described. 95

The outer oven wall is formed with an entrance opening 51, through which the articles A are inserted, the latter being removed through the exit opening 52. The 100 entrance opening 51 has a horizontal plate 53 therein located on a level or alined with the tops of the tiles 14 which constitute the floor of the revolving carrier, so that the articles or the like to be annealed can be 105 readily slid onto the tiles 14.

A wall 54 is built up within each compartment 7 and 8 of the fire chamber, and has its front face arranged in step-like formation, so as to cause the flames issuing 110 from the burners 9 to be deflected upwardly to enter the heating chamber 1 above the bottom thereof.

From the foregoing it will be seen that the floor or platform of the revolving carrier constitutes or forms the bottom of the annealing chamber. 115

What is claimed is:

1. An annealing oven including an annular heating chamber embodying a bottom 120 formed of two spaced annuli, a side wall seating on each annulus, and a top composed of a series of pairs of spaced tiles having their inner ends meeting at a point and connected by a tongue and groove joint and 125 having their lower ends seating on the upper ends of the side walls.

2. An annealing oven including an annular heating chamber embodying a bottom formed of two spaced annuli, a side wall 130

seating on each annulus, a top composed of a series of pairs of spaced tiles having their inner ends meeting at a point and connected by a tongue and groove joint and having their lower ends seating on the upper ends of the side walls, an annealing chamber including side walls each formed of tiles having their lower ends connected to the adjacent portions of the two annuli by a tongue and groove joint, and a roof 10 formed of series of pairs of tiles having their inner ends meeting in a point and connected by a tongue and groove joint and having their outer ends recessed and seating on and receiving the upper ends of said 15 tiles forming the side walls of the annealing chamber.

3. An annealing oven having a central opening, an annular annealing chamber having an open bottom, a vertical shaft arranged in said oven opening, a casting borne by said shaft having a horizontal portion and a depending apron formed with a horizontal ledge, said ledge being formed with 20 a raised lip at its outer end, a series of tiles seating on said horizontal portion of the casting and formed with downwardly extending projections, and a series of tiles seating on said ledge and engaged with the 25 lip thereof and having beveled upper ends engaged by said tile projections.

4. In an annealing oven, an annular heating chamber having an annular annealing chamber therein, said annealing chamber having an open bottom, a vertical shaft arranged in the center of the space defined by the annular heating chamber, a casing mounted on said shaft and arranged beneath the open bottom of the annealing 35 chamber, a second casting on the shaft, and a series of diagonal rods each connected 40 at their ends to the two castings.

5. In combination with an annealing oven having a central space and an annealing 45 chamber surrounding said space, a shaft arranged in said space, a rotating carrier on the shaft projecting into said open bottom of the annealing chamber, a conical shield surrounding the shaft and closing the lower 50 end portion of said central space of the oven, and means to support the shield from the oven.

6. In an annealing oven, an annealing chamber formed with an open bottom, a 55 heating chamber surrounding the sides and the top of the annealing chamber, a carrier forming the bottom of the annealing chamber, and a fire chamber divided into a plurality of compartments which communicate 60 with the heating chamber so as to inject the heat into the heating chamber so that the heat courses in opposite directions in the latter.

7. In combination with an annealing oven 65 formed with a central space and an an-

nealing chamber surrounding said space, a heating chamber surrounding said annealing chamber, a vertical shaft in said central oven space, a carrier on the shaft having a floor which extends into the annealing 70 chamber, a supporting structure composed of superimposed transversely arranged beams which engage on the oven top and extend over the said central space of the oven, said shaft having its upper end journaled in said supporting structure, a casting surrounding the shaft and supporting the inner side wall of the heating and annealing chambers, and a series of rods connected 75 to said casting and to said supporting structure to suspend said casting from the floor.

8. In an annealing oven, a pair of spaced horizontal annuli, a pair of vertical side walls at the peripheral portions of said annuli, a roof connected to said side walls, 80 a second pair of vertical side walls at the inner circumferences of the annuli spaced from the first named side walls, a roof connected to the second named side walls and being spaced from the first named roof, and 85 a carrier projecting into the space between said annuli.

9. In an annealing oven, an annular annealing chamber having an open bottom, a rotatable carrier alining with said open bottom of the annealing chamber, said carrier having a series of tiles on its upper face which tiles project into the annealing chamber, and a series of vertical tiles arranged 90 along one of the vertical faces of said carrier.

10. In an annealing oven, an annular annealing chamber having an open bottom, a heating chamber surrounding the sides and the top of said annealing chamber, a fire 105 chamber communicating with the heating chamber and having a partition therein to form two compartments, a source of heat in each compartment, and a partition in the heating chamber alined with said first 110 named partition to cause the heat issuing from said fire chamber to course in opposite directions in the heating chamber.

11. In an annealing oven having a central opening, an annular annealing chamber and an annular heating chamber surrounding the annealing chamber, said heating chamber surrounding said central opening of the oven and having its outer wall and that of the annealing chamber supported by the 120 oven, a vertical shaft in said oven opening, means surrounding the shaft to engage and support the inner walls of the annealing and heating chambers, means to support said first means from the oven top, 125 and a carrier on the shaft to carry the articles to be annealed through said annealing chamber.

12. In an annealing oven having a central opening, an annular annealing chamber and 130

- an annular heating chamber surrounding the annealing chamber, said heating chamber surrounding said central opening of the oven and having its outer wall and that of 5 the annealing chamber supported by the oven, a vertical shaft in said oven opening, means surrounding the shaft to engage and support the inner walls of the annealing and heating chambers, means to support 10 said first means from the oven top, a carrier on the shaft to carry the articles to be annealed through said annealing chamber, and means to inject heat into the heating chamber to cause same to flow in opposite directions 15 therein.
13. An annealing oven including an annealing chamber, a carrier therein, and tiles on the carrier arranged in end to end abutting relation having openings which communicate with opposite sides of the annealing chamber, the top faces of the tiles above the openings forming a continuous floor to receive the articles to be annealed.
14. An annealing oven including an annular heating chamber having a heat receiving inlet, means extending in the inlet to divide the chamber into two compartments, and means to supply heat to the inlet so that the heat will enter each compartment and flow 20 in relative opposite directions therein.
15. In an annealing oven, a pair of spaced annuli, a carrier rotating in the space between the annuli, an annealing chamber including side walls seating on and arranged 25 at the confronting portions of said annuli, and a heating chamber surrounding the annealing chamber and including side walls which seat on said annuli at the opposite portions thereof.
16. An annealing oven including a ring-like annealing chamber having an open bottom, a ring-like carrier projecting in said open bottom of the annealing chamber, and a heating chamber of ring-like form which 30 surrounds the annealing chamber.
17. An annealing oven including an annular heating chamber embodying a bottom formed of spaced annuli, a side wall seating on each annulus, and a top composed of 35 pairs of oppositely disposed tiles having their inner ends meeting at a point and having their lower ends seating on the upper ends of the side walls.
18. In an annealing oven, an annular heating chamber including a base formed of 40 two spaced annuli, a side wall seating on each annulus and a top carried by the side walls, an annealing chamber located within the heating chamber including a side wall seating on each annulus in spaced relation to the side walls of the heating chamber, a tongue and groove joint between the lower 45 ends of the side walls of the annealing chamber and said annuli, a roof supported on the upper ends of said side walls of the
- annealing chamber, and means holding the upper ends of the side walls of the annealing chamber in spaced relation to said side walls of the heating chamber.
19. In an annealing oven, a pair of spaced 70 annuli, an annealing chamber having a top and side walls one of the latter seating on one annuli and the other seating on the other of the annuli, a heating chamber surrounding the annealing chamber and having a top spaced from the top of the annealing chamber and side walls spaced from the side walls of the annealing chamber, one of the side walls of the heating chamber seating on one of the annuli and the other 75 side wall thereof seating on the other of said annuli, means to supply heat in the space between said chambers, and means to cause the heat to course in opposite directions in the said space.
20. In an annealing oven, an annular annealing chamber, an annular carrier in said chamber, a hollow casting seating on top of the carrier and having an apron which depends therefrom and extends over the outer 80 side face of the carrier, a series of vertical tiles arranged to overlie said apron and extending adjacent the upper face of the carrier, and a series of open-ended tiles seating on said casting and engaged with the upper 85 ends of said vertical tiles.
21. In an annealing oven, an annealing chamber, and a carrier having hollow open-ended tiles on its top which project in said chamber and vertical tiles along one side 90 thereof depending from the bottoms of the first named tiles.
22. In an annealing oven, an annealing chamber, a casting, a tile annulus seating on said casting, said annealing chamber 95 having one of its side walls seating on said tile annulus, said casting having a horizontal ledge, and vertical tiles seating on said ledge and interlockingly engaged with said tile annulus.
23. In an annealing oven, an annealing chamber, a casting, a tile annulus seating on said casting, said annealing chamber having one of its side walls seating on said tile annulus, and a series of vertical tiles arranged 100 on the outer face of said casting to act as heat protectors.
24. In an annealing oven, a horizontal annular annealing chamber, a horizontal annular heating chamber surrounding the annealing chamber, a fire chamber extending into the heating chamber at the periphery thereof so as to communicate therewith, a partition in the fire chamber dividing same into two compartments, and means to supply 105 heat to each of the fire chamber compartments.
25. In an annealing oven, a horizontal annular annealing chamber, a horizontal annular heating chamber surrounding the an- 110

nealing chamber, a fire chamber extending into the heating chamber at the periphery thereof so as to communicate therewith, a partition in the fire chamber dividing same 5 into two compartments, heat deflecting means alining with said partition and located between the two chambers and extending over the annealing chamber, and means

to supply heat to each of the fire chamber compartments.

In testimony whereof I hereunto affix my signature in the presence of two witnesses.

ALBERT J. MEIER.
